LIGHTING-FIXTURE FOR THEATERS AND PUBLIC HALLS.

1,054,759.

Specification of Letters Patent.

Patented Mar. 4, 1913.

Application filed January 16, 1912. Serial No. 671,512.

To all whom it may concern:

Be it known that I, GLOSS H. FOWLER, a citizen of the United States, residing at the city of Tacoma, in the county of Pierce and 5 State of Washington, have invented certain new and useful Improvements in Lighting-Fixtures for Theaters and Public Halls, of which the following is a specification.

The objects of my invention are, first, to 10 suitably light a motion picture theater or other public hall with the least interference with the exhibition on the screen or stage and with the greatest comfort to the audience; second, to provide a means for plainly 15 lighting motion picture theaters and public halls by indirect light reflected and diffused from panels as part of the lighting fixtures; and third, to secure the proper lighting of a 20 motion picture theater or other public hall at a minimum expense. I attain these objects by means of the device illustrated in the accompanying drawing in which—

Figure 1 is a plan of a small theater on 25 which is shown the manner in which my newly invented lighting fixture is located to light the audience; Fig. 2 is a sectional view of my invention showing how it is fixed on the side wall of the theater or hall; Fig. 3 is a sectional view the same as Fig. 2, and 30 showing an adjusted position of the fixture on the side wall; and Fig. 4 is an elevation of my invention from a point of view at right angle with the side wall.

Similar characters refer to similar parts 35 in the several views.

For a time motion picture theaters were 40 operated with all lights turned off while the pictures were being shown on the screen. This made the theater dark and uninviting to timid people, particularly women and children. Later light fixtures with colored 45 shades were introduced and are still used to dimly light the theaters and enable the people to find their way in and out during 50 the progress of the show.

With my newly invented lighting fixture, 55 a theater can be clearly lighted so that one can not only find his way in and out with ease but can recognize acquaintances. The decorative and artistic features of the 60 theater interior can be seen and appreciated. All these results are secured without interfering with the scenes on the screen or stage.

My newly invented lighting fixture 55 comprises a semi-cylindrical reflector shade A, in

which are placed and concealed from view the electric lights B—B. This semi-cylindrical shade is adjustably attached to the side or edge of panel frame C made of suitable material. The curved panel frame C is 60 provided with the side cleats D and D' designed to form a panel in which cardboard or heavy paper or suitable material can be slipped in and out as desired. One side of the panel frame opposite the light shade is 65 hinged to a wall strip E at approved height from the floor, to allow the panel frame to be adjusted to the most suitable angle with the wall by means of the adjuster arm F, also hinged to the wall at G and its outward 70 end engaged to slide and clamp in the slot H as shown in Figs. 2 and 3.

The panel frame being adjustable, it is intended that the panels placed nearest the stage or screen shall be about at right angles 75 with the side of the theater, and that the angle of each following panel as placed along the side walls at suitable distances toward the rear shall decrease until the last panel is placed at an angle of about thirty 80 degrees with the walls as illustrated at I—L in Fig. 1. This arrangement, aside from not interfering with a perfect view of the screen or stage, affords a better view of the several panels from the audience than 85 any other. At the same time the panels adjusted at any angle with the walls of thirty degrees or more, do not expose the lamps or their direct rays to the audience.

The panel slide cleats D and D' are located near the sides of the panel frame as 90 shown and stand out about one-half an inch from the curved face of the frame. The cleat next the light reflector shade A is placed about six inches therefrom. This six 95 inch space and the slide cleat is painted a dead black or dark color. This dark surface in conjunction with the raised cleat eliminates the glare of the electric lights B—B on the surface of the panel C nearest 100 the reflector shade, and the panel thus lighted and on account of its concave surface receives an even distribution of light over its entire surface. The six inch space between the reflector shade and the slide 105 cleat has the further advantage of allowing a full view of the panel by the audience from the rear of the house up to a line abreast of the panel.

The reflector shade being pivotally at 110

tached or hinged to the edge of the panel frame can be adjusted to confine the light to any desired distance on the wall back of where it is hinged to the wall. The panel being white or of suitably light color, it reflects and diffuses a soft clear light over the audience that is very comfortable and restful.

While the audience and all features of the room are plainly discernible, the pictures on the screen are as clearly visible as in a dark room. This is due to the fact that all the light from my newly devised fixture is reflected and diffused away from the screen or stage.

The clearer and more restful light produced by my invention is found to require less electric current than the common dark shaded fixture now used.

20 The cardboard or paper panel, in addition to being a light surface to reflect and diffuse the light thereon, can be used as an advertising surface on which business advertisements can be printed and displayed 25 in an attractive and effective manner. The paper panel being made to run loosely into the slide, cleats D—D' can be changed and varied as often as desired. By this means my lighting fixture can be made both useful 30 and profitable to the owner.

My lighting fixture is not to be confined to be used on side walls only. It can be used on the ceiling and for bulletin boards. It can be used to form a border or frame about 35 the screen in motion picture and other theaters; the light being thrown away from the screen tends to accentuate the darkness of the screen. The fixture can also be used about the entrances in front of a theater or in 40 other halls or lobbies not well lighted by other methods.

I am aware that concave and other surfaces have been previously used with lights thrown in front of them for signs and for 45 street advertising. I am also aware that various forms of diffused and indirect light fixtures are now in use, but what I claim as my invention is the novel idea of combining in a lighting fixture a diffused light reflected 50 away from the screen or stage with a surface or panel for the radiating and diffusing surface.

While the drawing and this specification sets forth the present and preferred form of 55 my invention, I reserve the right to vary the same when conditions require, to obtain the most practical results without departing from the spirit and novelty of the device.

Having described my invention and set 60 forth its merits what I claim is:—

1. An indirect lighting fixture for theaters and public halls, comprising a con-

cave frame, a reflecting and diffusing panel mounted in said frame, a semi-cylindrical reflector hinged to one side of said frame, 65 and one or more sources of light mounted in said reflector.

2. A lighting fixture for theaters and public halls, comprising a panel frame carrying a light diffusing panel, a reflector arranged at an outer edge of said frame, and a light supplying medium inclosed within the reflector, the latter opening toward said panel and being adjustable relatively thereto. 70

3. A lighting fixture for theaters and public halls, comprising a panel frame carrying a light diffusing panel, a reflector arranged at an outer edge of said frame, a light supplying medium inclosed within the reflector, the latter opening toward said panel, and a support to which the frame is hinged on an axis parallel to the reflector. 75

4. A lighting fixture for theaters and public halls, comprising a panel frame carrying a light diffusing panel, a reflector arranged at an outer edge of said frame, a light supplying medium inclosed within the reflector, the latter opening toward said panel, a support to which the frame is hinged on an axis parallel to the reflector, and means for 85 adjusting and holding the frame at different positions about its hinge connection as a center.

5. A lighting fixture for theaters and public halls, comprising a frame having parallel panel retaining cleats, a reflector arranged at an outer edge of said frame parallel to said cleats and spaced from the adjacent cleat, the frame being surfaced with a dark color in the space intervening between 100 the reflector and the cleat adjacent thereto, and a light supplying medium inclosed within the reflector, the latter opening toward said frame. 95

6. A lighting fixture for theaters and public halls, comprising a frame carrying a light diffusing panel, a reflector arranged at an outer edge of the frame parallel to and spaced from the panel, the frame being surfaced with a dark color in the space intervening between the reflector and the panel, means of support for the frame at that edge thereof which is opposite to the reflector, the frame projecting laterally from its support, and a light supplying medium inclosed within the reflector, the latter opening toward the panel. 110 115

In testimony whereof I affix my signature in presence of two witnesses.

GLOSS H. FOWLER.
